THERMOELECTRIC SAFETY CONTROL AND
SWITCH

Richard K. Engholdt, Milwaukee, Wis., assignor
to Milwaukee Gas Specialty Company, Milwaukee, Wis., a corporation of Wisconsin

Application March 23, 1939, Serial No. 263,589

17 Claims. (Cl. 200—87)

This invention relates to a thermoelectric safety control and switch and, more particularly, is directed to an improved thermoelectric safety control and switch for use with heating and other apparatus, although it is not limited to such use but may be employed elsewhere as desired.

The particular device which I shall describe hereinafter in connection with the drawings is a thermoelectric safety control and switch for opening and closing a control circuit for heating apparatus, for example the circuit for a solenoid or motor valve which is held in open or operating position to permit a supply of operative energy to the apparatus as long as the control circuit for the valve is closed and which moves to closed position to shut off the supply of operative energy to the apparatus on current interruption.

The invention, however, is not limited to use in the particular manner above set forth, nor in particular manner shown in the accompanying drawings which are for purposes of illustration only and are not to be construed as a definition of the scope of the invention, reference being had to the appended claims for that purpose.

For example, the thermoelectric safety control and switch of the present invention may be used in conjunction with valves that require current for both opening and closing, and the thermoelectric safety control and switch may be used for operating alarm circuits and for all similar purposes.

One of the main objects of the present invention is to provide, in a thermoelectric safety control and switch of the character described, a switch, means for operating the switch, and an electromagnet having an armature, which, when attracted, places the switch under the control of the operating means and, when retracted, prevents operation of the switch by the operating means—in other words, the switch is operable only when the electromagnet is energized and the armature is in attracted position, and is inoperative when the electromagnet is deenergized and the armature is in retracted position.

In its more specific aspects, the switch operating means is operative to set the armature to attracted position, and the movement of the armature to retracted position on deenergization of the electromagnet operates the switch to safety position, for example to position for movement of the valve to closed position shutting off the supply of operative energy to the apparatus, or to position for operating an alarm circuit or any other desired circuit.

Another object of the invention is to provide, in a device of the character described, a snap acting toggle switch which is adapted to be operated by the switch operating means only when the armature is in attracted position and is prevented from being operated by the switch operating means when the electromagnet is deenergized and the armature is in retracted position.

10 It is also an object of the present invention to provide a combined thermoelectric safety control device and switch of relatively simple and inexpensive construction and which may be installed and operated conveniently and effectively; also a device of this character composed of relatively few parts and adapted for convenient and expeditious manufacture and assembly, and which operates quickly, positively, and effectively.

20 Further objects and advantages of the invention will be apparent from the following detailed description, taken in connection with the accompanying drawings in which:

Figure 1 is a fragmentary and more or less 25 diagrammatic view showing an embodiment of the present invention in a pilot burner and main burner fuel supply system;

Figure 2 is a side view of the thermoelectric safety device and switch;

30 Figure 3 is a vertical section through the thermoelectric safety device and switch, taken on the line 3—3 of Figure 2;

Figure 4 is a detail view, partially broken away 35 and showing the snap acting toggle switch of the thermoelectric safety device and switch; and

Figure 5 is a detail perspective view showing the insulated contacts which cooperate with the roller contact of the switch.

Referring now to the drawings which, as 40 above set forth, are for the purpose of illustrating one embodiment of the invention and one particular manner of using the invention and are not to be construed as a definition of the scope of the invention, either as to the form of the embodiment illustrated or as to the illustrated use of the invention, the burner 10 is any suitable or preferred burner, such as the main burner of a hot water heater, gas furnace, oil heater, automatic space heater, domestic gas range, or it may be a conversion burner, or any other burner.

Associated with the main burner 10 is the usual or any suitable or preferred pilot burner, indicated more or less diagrammatically at 12, 50 which pilot burner is intended to remain lighted

for the purpose of relighting the main burner upon extinguishment thereof. The pilot burner 12 is supplied with gaseous or any other suitable fuel by a tube 13 connected, for example, to the fuel supply conduit 14 which supplies fuel to the main burner.

The conduit 14 is provided with a solenoid or motor valve 15, which valve has a control circuit 16 connected, for example, through a transformer 17, to a suitable source of current, for example to an alternating current circuit 18. For purposes of illustration only, it may be assumed that the valve 15 is of a character to be maintained in open position for a supply of fuel or operative energy to the burner 10 as long as the circuit 16 is closed, and to operate to closed position to shut off the supply of operative energy to the apparatus upon interruption of the current by opening the circuit 18.

Of course, by the simple expedient of making additional circuit connections with the switch of the thermoelectric safety control and switch, it may be used in conjunction with valves that require current for both opening and closing. Also, the circuit 16 may be an alarm circuit, or any other desired circuit may be controlled by the switch within the scope of the broader aspects of the present invention.

The thermoelectric safety control and switch, designated in its entirety at 20, comprises a lead connection cap and magnet and armature housing assembly of the general character disclosed and claimed in the copending application of Clarence Wantz, Serial No. 239,790, filed November 10, 1938.

The lead connection cap 22, which is preferably formed of "Bakelite" or any other suitable or preferred insulating material, may be of the form shown, or of any other suitable or preferred form. It has at its lower end, as viewed in Figure 3, an integral cylindrical extension 23 which fits into an opening 24 in one arm of an angular supporting bracket 25. The cap 22 is fastened in place on the bracket 25, for example by cap screws 26.

The magnet housing 30 is in the form of an upwardly opening cup-shaped metal shell mounted on the cap 22, for example by a secure pressed fit engagement of its open upper end in the cap 22 at 32. The housing or shell 30 is reduced at its lower end at 33, and the armature housing 34, which is also in the form of an upwardly opening cup-shaped metal shell, is mounted on the shell 30, for example by a secure pressed fit engagement of its open upper end telescopically over the reduced lower end 33 of the shell 30. The lower end of the shell 30 is preferably reduced, as shown. The electromagnet comprises a generally U-shaped magnet frame 36 positioned within the shell 30 with its legs extending through openings in the lower end of this shell and presenting pole ends within the armature housing 34. The magnet frame 36 has a threaded stud 37 integral therewith, or welded, or otherwise rigidly joined thereto. This stud 37 extends into an opening or recess 38 in the top of the cap 22, and has threaded engagement with a nut member 39 for clamping the magnet frame rigidly and, at the same time, removably in place. The nut 39 has a kerf 40 for engagement by a screw driver or other suitable tool, and a spring washer may be provided between the nut member 39 and the bottom of the recess 38 as indicated at 41.

Fixed rigidly in the cap 22, as for example by

5 molding the insulating material of the cap thereto and extending endwise from the cap, are a pair of spaced metallic terminal connectors 42 and 43 having aligned openings 44 and split outwardly of these openings as shown at 45. The electromagnetic coil 46 surrounds the legs of the magnet frame 36, and the leads or ends of this coil extend out through the terminal connectors 42 and 43 and have their bared ends connected to the terminals 42 and 43 at 47 and 48, respectively, in a manner to have good conducting contact therewith. The connections at 47 and 48 are shown disposed outside of the cap 22 and laterally of the openings for receiving the terminal means on the thermocouple lead conductors. The coil 46 is preferably covered with insulation between its bared ends at 49. Suitable insulation may be interposed between the turns of the coil 46 and the legs of the magnet frame 36, and between the lower end of the shell 30 and the adjacent end of the coil 46, as shown, by way of example, at 51 and 52, respectively.

20 The armature 55 is disposed in the armature housing 34 and is adapted to be held in attracted position against the pole ends of the magnet frame 36 upon energization of the electromagnet. The armature 55 is of disc-like form and is secured to the upper end of a reciprocating stem or plunger 57. The attachment of the armature to the stem or plunger 57 at 58 is preferably sufficiently loose, as indicated at 59, to permit self-accommodation of the armature to the pole ends of the magnet frame by a generally universal movement of the armature upon the upper end of the stem 57. The stem 57 is disposed generally concentrically of the armature housing 34 and extends downwardly for reciprocating movement through an opening 60 in the lower end of the housing 34.

25 The thermocouple and lead connection therefor are of the general character disclosed and claimed in Oscar J. Leins Patent No. 2,126,564, granted August 9, 1938, and in the copending application of Clarence Wantz hereinbefore identified.

30 The thermocouple 65 comprises an outer tubular metallic thermocouple member 66 and an inner metallic thermocouple member 67 disposed within the outer thermocouple member and joined at one end to the outer thermocouple member to form the thermal junction 68, which is placed in position to be heated by the pilot light 12'. An inner lead conductor 69 is joined to the inner thermocouple member to form an internal thermal junction 70, and an outer tubular lead conductor 71 is connected to the outer thermocouple member through a sleeve 71' to form a third thermal junction 72. The outer lead conductor 71 encloses the inner lead conductor and, with the outer thermocouple member, constitutes an enclosure about the inner thermocouple member and the inner lead conductor and the inner thermocouple junction 70. The inner lead conductor 69 is insulated 35 from the outer lead conductor by a wrapping of insulation on the inner lead conductor as indicated at 74, or by an oxide coating, or otherwise as desired.

35 The inner and outer lead conductors 69 and 71 are preferably of a character that will permit bending, as desired, to permit disposing the thermocouple in any desired position. At the same time, the lead connection is preferably of a character to support the thermocouple in any desired

position, although supporting brackets or other means may be employed for supporting the thermocouple and lead connection. At the opposite end, the inner lead conductor 69 extends from the outer lead conductor 71 and has a metallic terminal sleeve 76 fixed thereon in good conductive contact therewith and spaced from the end of the lead conductor 71. An insulating sleeve 77 is interposed between the terminal sleeve 76 and the adjacent end of the outer lead conductor 71.

A quick detachable connection is thus provided between the thermocouple leads and the terminals 42 and 43 for the electromagnet coil 46. The thermocouple is connected to the terminals 42 and 43 by slipping the terminal end of the thermocouple lead means through the opening 44 in one terminal 43 and into the opening 44 in the other terminal, with the terminal sleeve 76 in the opening 44 in one terminal 42 and the end of the tubular thermocouple lead 71 in the opening 44 in the other terminal 43. The screws 80 are then tightened to clamp the split portions 45 of the terminals 42 and 43 into good conductive contact and gripping engagement with the terminal sleeve 76 and tubular lead 71, respectively. The thermocouple is disconnected from the device by loosening the screws 80 and withdrawing the terminal end of the thermocouple leads from the terminals 42 and 43.

The snap acting toggle switch, designated in its entirety at 100, is of existing form except for the manner in which it is combined with the thermoelectric safety control of the present invention, and, for certain features, to the end of effecting the desired combination for the purposes of the present invention.

The switch 100 comprises a pair of aligned contacts 101 and 102 and a third contact 103 insulated from each other and bound together with a plurality of insulating strips 104. The contacts 101, 102 and 103 and the insulating strips 104 are secured together into a unitary assembly by securing means indicated at 105.

This contact and insulating strip assembly is secured at 106 in a metal cradle 107 which is pivoted to turn freely on the inner end of a sleeve 108 which extends inwardly from the arm 109 of the bracket 25, which arm 109 is disposed at right angles to the arm of the bracket to which the thermoelectric safety control is secured. A shaft 110 is journaled for rotation in the sleeve 108 coaxial with the axis of swinging movement of the switch cradle 107. A knob or finger piece 112 is fixed on the outer end of the shaft 110, for example by a screw 114. The shaft 110 is adapted to be rotated by grasping the finger piece 112 and turning the same.

Fixed upon the inner end of the shaft 110 to turn therewith is a switch actuating arm 115. The outer end of the arm 115 is turned back, and the end has a rounded point at 116. This pointed end 116 engages in the bifurcated outer end of a contact roller actuating member 118 and in a depression 119 in an element 120 which is slipped over the bifurcated outer end of the member 118. The inner end of the member 118 has an insulating tip 120' which is notched to engage the reduced intermediate portion 121 of the roller contact 122. A coiled spring 123, surrounding the member 118 and interposed between the element 120 and an abutment 124 on the member 118, snaps the roller contact 122 from the position shown, in which it engages the contacts 102 and 103, to the opposite end of the arcuate track 125, at which position it engages the contacts 101 and

103. The intermediate insulated portion of the track 125 is preferably raised to engage in the reduced intermediate portion of the contact roller 122 to guide the same in its movement.

One end of the roller contact 122 makes contact at all times with the contact 103, which is of full length, with a contact edge presented throughout the full length of the arcuate track 125 for continued contact with the roller 122. The contacts 101 and 102 are insulated from each other at 126. It will thus be apparent that when the roller 122 is in the position shown, it bridges the contacts 102 and 103, and when snapped to the opposite position by the toggle action upon turning the finger piece 112, it bridges the contacts 101 and 103. Each contact 101, 102 and 103 has a terminal 130 for connection, for example, to a three-wire control circuit. In the illustrated embodiment of the invention, the control circuit is a two-wire circuit, one wire or conductor 16 being connected to the terminal of the contact 102 and the other wire or conductor 16' being connected to the contact 103. It will thus be apparent that when the roller contact 122 is snapped by the toggle action into engagement with the contacts 102 and 103, the circuit 16 is closed, thereby energizing the valve 15 to maintain same in open position for supplying operative energy to the apparatus. When the roller contact 122 is snapped to its opposite position, it ceases to bridge the contacts 102 and 103, and the circuit 16 is interrupted, thereby releasing the valve 15 for movement, for example, by a spring (not shown) to closed position, shutting off the supply of operative energy to the apparatus.

The outer end of the stem or plunger 57 of the thermoelectric control device is bifurcated and fits over and is pinned at 140 to a connecting member 142, which connecting member is, in turn, pivoted by one of the pins or a screw 106 to the switch cradle 107. A helical spring 144 is interposed between a plate 145 at the bottom of the armature housing 34 and the shoulder means 146 on the connecting link 142.

The operation of the device is as follows:

When the pilot light 12' is burning, the heat thereof upon the thermal junction 68 produces a thermoelectric current in the coil 46. The magnet frame 36 and armature 55 are preferably formed of an alloy of relatively low magnetic reluctance, and, as a result, the relatively weak thermoelectric current produces a magnetic field of sufficient strength so that when the armature 55 is placed in contact with the pole ends of the magnet frame as shown in Figure 3, the magnetic attraction holds the armature in attracted position against the magnet frame with a force greater than the force exerted by the spring 144, thereby holding the switch cradle 107 and contact assembly 101, 102 and 103 in the position as shown in Figure 3.

If the pilot flame is extinguished, the holding action of the electromagnet ceases to be sufficient to hold the armature 55 in attracted position, and the spring 144 swings the switch cradle 107, and the contacts 101, 102 and 103 carried thereby, clockwise as viewed in Figure 3, generally to the position shown in dotted lines. Movement of the cradle 107 from the full line position to its dotted line position as the armature moves to retracted position moves the contact 102 out of engagement with the roller contact 122, thereby opening the control circuit 16 and releasing the shutoff valve 15 for movement to closed position.

When it is desired to reset the device, the finger piece 112 is grasped and turned in a direction to swing the lower end of the actuating member 118, as viewed in Figure 4, counterclockwise, the member 118 being positioned opposite the position in which it is shown in Figure 4 before the finger piece is turned. It is to be understood that the member 118 has assumed this position opposite to that shown in Figure 4, relative to the carrier or cradle 107 and its contacts, for example by swinging of the carrier 107 to the dotted line position shown in Figure 3 upon release of the armature by deenergization of the electromagnet. Alternatively, the member 118 and the roller contact 122 actuated thereby may be positioned opposite the position shown in Figure 4 by turning the finger piece in a direction to actuate the roller contact 122 to such position out of engagement with the contacts 102, 103 when the armature is held in attracted position.

Assuming that the member 118 is positioned opposite the position shown in Figure 4, rotation of the finger piece 112 in a counterclockwise direction as the parts are viewed in Figure 4 causes the member 118 to engage the insulating strip assembly at 160 and, through this assembly, to swing the cradle 107 therewith. This swinging movement of the cradle in a counterclockwise direction, as viewed in Figure 3, actuates the stem 51 inwardly and sets the armature 55 into attracted position. As positioned at the beginning of this resetting movement, the shaft 110 is stopped against turning movement in the opposite direction, or against retrograde turning movement, by engagement of a pin 162 thereon with a stop 163 (Figure 2).

If the pilot burner 12' is lighted and sets up a thermoelectric current to hold the armature in attracted position as it is reset to this position by turning the finger piece 112, the cradle 107 is held against swinging movement in the opposite direction with the switch actuating arm 115. At the same time, in resetting the armature to attracted position the pin 162 moves away from the stop 163. Therefore, the shaft 110 and the arm 115 carried thereby may now be turned in the opposite direction, and the cradle 107, being held against movement with the shaft 110 by the magnetic attraction which holds the armature attracted, turning of the knob 112 in the opposite direction snaps the contact 122 into engagement with the contacts 102 and 103, thereby closing the circuit 16 to actuate the valve 15 to open position.

If, on the other hand, the pilot burner is not ignited to produce the thermoelectric current for holding the armature in attracted position, the switch cradle 107 will follow the movement of the shaft 110 and switch actuating member 118, so that turning of the shaft in the opposite direction after resetting the armature to attracted position will turn the contact assembly 101, 102 and 103 freely therewith so as not to close the circuit 16. In other words, unless the electromagnet is energized and the armature held in attracted position, there will be no movement of the contact roller 122 relative to the cooperating contacts, thus making it impossible to close the circuit 16 when the electromagnet is deenergized.

It will be understood that where the fuel supply tube 13 for the pilot burner is connected to the fuel supply duct 14, the connection will preferably by-pass the valve 15 or be disposed

anterior to the valve 15 so that there will be a supply of fuel to the pilot burner when the valve 15 is closed.

I do not intend to be limited to the precise details shown or described.

I claim:

1. In a device of the character described, in combination, a control device having an electromagnet provided with an armature and adapted when energized to hold said armature in attracted position and when deenergized to release said armature for movement to retracted position, switch means controlled by said electromagnet and comprising switch contact means mounted for swinging movement and connected to said armature, toggle actuated and snap acting contact means cooperable with said first contact means, means for operating said last contact means, said armature when held in attracted position permitting actuation of said last contact means relative to said first contact means by said operating means and, when retracted, preventing actuation of said last contact means relative to said first contact means, said armature being set to attracted position by the actuation of said operating means, and means for preventing retrograde movement of said operating means from substantially the position from which it is operated to set said armature into attracted position.

2. In a device of the character described, in combination, a control device having an electromagnet provided with an armature and adapted when energized to hold said armature in attracted position and when deenergized to release said armature for movement to retracted position, contact means connected to said armature, cooperating contact means adapted for actuation in one direction to actuate said first contact means in one direction and thereby set said armature in attracted position through the connection between the armature and said first contact means, said cooperating contact means being adapted for actuation in the opposite direction relative to said first contact means when the electromagnet is energized and the armature is held in attracted position and actuating said first contact means therewith in the opposite direction when the electromagnet is deenergized, said cooperating contact means comprising a toggle actuated snap acting roller contact and said first contact means comprising contacts insulated from each other and adapted for contact with said roller contact, and means for operating said roller contact.

3. In a device of the class described, in combination, a control device having an electromagnet provided with an armature and adapted when energized to hold said armature in attracted position and when deenergized to release said armature for movement to retracted position, a support, contact means pivoted on said support and connected to said armature, a shaft mounted for rotation coaxially with respect to the pivot for said first contact means, a finger piece for turning said shaft, contact means cooperating with said first contact means and adapted to be actuated in opposite directions by said shaft upon turning movement thereof, and stop means for preventing retrograde actuation of said cooperating contact means from substantially the position normally occupied by said contact means when the electromagnet is deenergized.

4. In a device of the class described, in com-

bination, a control device having an electromagnet provided with an armature and adapted when energized to hold said armature in attracted position and when deenergized to release said armature for movement to retracted position, a support, contact means pivoted on said support and connected to said armature, a shaft mounted for rotation coaxially with respect to the pivot for said first contact means, a finger piece for turning said shaft, contact means cooperating with said first contact means and adapted to be actuated in opposite directions by said shaft upon turning movement thereof, and spring means interposed between a relatively fixed abutment and said first contact means for actuating said first contact means to a safety position and said armature to retracted position when the electromagnet is deenergized.

5. In combination, first contact means mounted for swinging movement in opposite directions, holding means comprising an electromagnet which, when energized, is adapted for holding said contact means against swinging movement in one direction, operating means rotatable in one direction to move said first contact means to the position in which said first contact means is held by said electromagnet when energized, and second contact means actuated relative to said first contact means by rotation of said operating means in the opposite direction only when said first contact means is held by said electromagnet.

6. In combination, first contact means mounted for swinging movement in opposite directions, holding means comprising an electromagnet which, when energized, is adapted for holding said contact means against swinging movement in one direction, operating means rotatable in one direction to move said first contact means to the position in which said first contact means is held by said electromagnet when energized, second contact means actuated relative to said first contact means by rotation of said operating means in the opposite direction only when said first contact means is held by said electromagnet, and means for limiting rotation of said operating means to one direction from the position from which it is operated to move said first contact means to the position in which said first contact means is held by said electromagnet and permitting rotation of said operating means in the opposite direction from said last mentioned position.

7. In combination, first contact means mounted for swinging movement in opposite directions, holding means comprising an electromagnet which, when energized, is adapted for holding said contact means against swinging movement in one direction, operating means rotatable in one direction to move said first contact means to the position in which said first contact means is held by said electromagnet when energized, second contact means actuated relative to said first contact means by rotation of said operating means in the opposite direction only when said first contact means is held by said electromagnet, and a toggle connection between said operating means and said second contact means for providing a snap action of said second contact means.

8. In combination, a pivoted contact carrier, first contact means carried thereby, an electromagnet, an armature for said electromagnet which, when attracted, is adapted to hold said contact carrier against turning movement in one direction, operating means rotatable in one direction to move said armature to attracted position

5 and to swing said contact carrier to the position in which it is held when said armature is attracted, and second contact means operatively connected to said operating means to be actuated by said operating means into contact with said first contact means to complete an electric circuit by rotation of said operating means relative to said contact carrier in the direction in which movement of said contact carrier is restrained by attraction of said armature by said electromagnet.

9. In combination, a pivoted contact carrier, first contact means carried thereby, an electromagnet, an armature for said electromagnet which, when attracted, is adapted to hold said contact carrier against turning movement in one direction, operating means rotatable in one direction to move said armature to attracted position and to swing said contact carrier to the position in which it is held when said armature is attracted, second contact means adapted to be actuated into contact with said first contact means to complete an electric circuit by rotation of said operating means relative to said contact carrier in the direction in which movement of said contact carrier is restrained by attraction of said armature by said electromagnet, and a toggle connection between said operating means and said second contact means for providing a snap action of said second contact means.

10. In combination, a pivoted contact carrier, first contact means carried thereby, an electromagnet, an armature for said electromagnet which, when attracted is adapted to hold said contact carrier against turning movement in one direction, operating means rotatable in one direction to move said armature to attracted position and to swing said contact carrier to the position in which it is held when said armature is attracted, second contact means operatively connected to said operating means to be actuated by said operating means into contact with said first contact means to complete an electric circuit by rotation of said operating means relative to said contact carrier in the direction in which movement of said contact carrier is restrained by attraction of said armature by said electromagnet, and means for moving said armature to retracted position upon deenergization of said electromagnet with an accompanying swinging movement of said contact carrier in a direction to disengage said first contact means from said second contact means to open the electric circuit.

11. In combination, a pivoted contact carrier, a pair of contacts carried by said carrier for pivotal movement therewith, holding means comprising an electromagnet which, when energized, is adapted for holding said carrier and the contacts carried thereby against swinging movement in one direction, operating means rotatable in one direction to move said carrier and the contacts carried thereby to the position in which said carrier and contacts are held by said electromagnet when energized, a roller contact, and a toggle connection between said operating means and said roller contact for actuating said roller contact into position bridging said first contacts by rotation of said operating means in the opposite direction only when said carrier and said first contact means are held by said electromagnet.

12. In combination, a pivoted contact carrier, a pair of contacts carried by said carrier for pivotal movement therewith, holding means comprising an electromagnet which, when energized, is adapted for holding said carrier and the con-

tacts carried thereby against swinging movement in one direction, operating means rotatable in one direction to move said carrier and the contacts carried thereby to the position in which said carrier and contacts are held by said electromagnet when energized, a roller contact, a toggle connection between said operating means and said roller contact for actuating said roller contact into position bridging said first contacts by rotation of said operating means in the opposite direction only when said carrier and said first contacts are held by said electromagnet, and means for actuating said carrier and said first contacts in a direction to move said first contacts out of contact with said roller contact upon deenergization of said electromagnet.

13. In combination, a pivoted contact carrier, a pair of contacts carried by said carrier for pivotal movement therewith, holding means comprising an electromagnet which, when energized, is adapted for holding said carrier and the contacts carried thereby against swinging movement in one direction, operating means rotatable in one direction to move said carrier and the contacts carried thereby to the position in which said carrier and contacts are held by said electromagnet when energized, a roller contact, a toggle connection between said operating means and said roller contact for actuating said roller contact into position bridging said first contacts by rotation of said operating means in the opposite direction only when said carrier and said first contacts are held by said electromagnet, means for actuating said carrier and said first contacts in a direction to move said first contacts out of contact with said roller contact upon deenergization of said electromagnet, and means for limiting rotation of said operating means to one direction from the position from which it is operated to move said carrier and the contacts carried thereby to the position in which said carrier and contacts are held by said electromagnet and permitting rotation of said operating means in the opposite direction from said last-mentioned position.

14. In combination, a pivoted contact carrier, first contact means carried by said carrier, spring means for turning said carrier in one direction, an electromagnet, an armature for said electromagnet and having pivotal connection with said carrier to hold same when attracted against actuation by said spring means, operating means rotatable in one direction to move said armature to attracted position against the action of said spring means and said carrier to the position in which it is held when said armature is attracted, and second contact means adapted to be actuated into contact with said first contact means to complete an electric circuit by rotation of said operating means relative to said contact 60

5 carrier in the direction in which movement of said contact carrier is restrained by attraction of said armature by said electromagnet and only when said contact carrier is held by said electromagnet, said spring means actuating said carrier in a direction to open the circuit when said electromagnet is deenergized to release said armature.

15. In combination, a pivoted contact carrier, 10 first contact means carried by said carrier, spring means for turning said carrier in one direction, an electromagnet, an armature of said electromagnet and having pivotal connection with said carrier to hold same, when attracted, against actuation by said spring means, operating means rotatable in one direction to move said armature to attracted position against the action of said spring means and said carrier to the position in which it is held when said armature is attracted, 20 second contact means adapted to be actuated into contact with said first contact means to complete an electric circuit by rotation of said operating means relative to said contact carrier in the direction in which movement of said contact carrier is restrained by attraction of said armature by said electromagnet, said spring means actuating said carrier in a direction to open the circuit when said electromagnet is deenergized to release said armature, and a toggle connection 25 between said operating means and said second contact means for providing a snap action of said second contact means.

16. In combination, an electromagnet, an armature for said electromagnet, first contact 30 means connected to said armature, second contact means for engagement with said first contact means, and means operable to reset said armature to attracted position and operatively connected to said second contact means to actuate said second contact means into engagement with said first contact means only when said armature is held in attracted position by said electromagnet.

17. In combination, an electromagnet, an armature for said electromagnet, first contact means connected to said armature, second contact means for engagement with said first contact means, and means operable to reset said armature to attracted position and operatively connected to said second contact means to actuate said second contact means into engagement with said first contact means only when said armature is held in attracted position by said electromagnet, resetting movement being imparted to said armature by movement of said operating means in one direction and said second contact means being actuated into engagement with said first contact means by said operating means upon movement thereof in a different direction. 55
